METHOD OF CONVERTING ALDEHYDES
TO ACIDS

William J. Hale, Midland, Mich.

No Drawing. Application October 26, 1931,
Serial No. 571,281

18 Claims. (Cl. 260—116)

The present invention relates to an improved method of converting aliphatic and aromatic aldehydes to their corresponding acids.

In the past one well known method of preparing aliphatic acids consisted in general of a two-stage process involving first the dehydrogenation of alcohol into the corresponding aldehyde by means of metallic catalysts, and the subsequent oxidation of the aldehyde and hydrogen formed into the corresponding acid and water respectively. The second stage of the process, that is to say the oxidation of the aldehyde to the acid, was effected through the agency of an oxygen supplying material, such as copper oxide.

The present invention is based upon the discovery that aldehydes may be converted into their corresponding acids by a process which, in sharp contradistinction to prior methods, does not involve the utilization of direct oxidizing agents. Briefly considered the present novel process comprehends the hydration of aldehydic starting material to the corresponding aldehydrol and then the immediately subsequent dehydrogenation of the aldehydrol to the corresponding acid. The process is further characterized by being effectuated at a relatively low temperature. In order to insure success of the operation the conditions of catalysis should be carefully chosen and regulated.

It has been recognized heretofore that when acetic acid, for example, is prepared by the usual process, that is to say by the dehydrogenation of alcohol and the subsequent oxidation of acetaldehyde, considerable portions of the acetaldehyde and hydrogen pass through the oxidation zone unchanged. It has furthermore been observed that this occurs even in the presence of a large excess of oxidizing material, and even when the temperature of operation is maintained well below the point of incipient complete combustion of the organic compounds into carbon dioxide and water.

As early as 1906 Jóhaan Walter (D. R. P. 168291) indicates that acetic acid, as well as acetaldehyde, occurs among the products of incomplete combustion of ethyl alcohol in the presence of considerable water vapor. It is furthermore shown (D. R. P. 185932—1907) that acetic acid with hydrogen in contact with metals and rough surfaces in general yield acetaldehyde and water in the neighborhood of 300° C. Walter's observations receive substantiation when we consider the dehydrogenated ethyl alcohol (that is the acetaldehyde) interacting with water to yield

acetic acid and hydrogen; the removal of the hydrogen through combustion only facilitating the drift toward acetic acid.

As a result of considerable experimentation I have found, as noted above, that aldehydes can be converted into the corresponding acid without employing the usual method, that is to say utilizing either oxygen or potentially available oxygen. While not confining myself to any statement as to the rationale of the reaction, it is evident that the process involves the hydration of the aldehyde to the aldehydrol and the subsequent dehydrogenation of this to the acid, as will appear more fully hereinafter.

It is to be noted that the inference of the formation of an intermediate more or less unstable aldehydrol type of compound has many points of support. Ramsay & Young (Phil. Trans. 1886—1,117) first announced the possibility of aldehydrol through a study of heat evolution and volume contraction directly upon mixing acetaldehyde with water. Perkins (Chem. Soc. 51,816—1887) and Homfray (Chem. Soc. 87,1435—1905) established the existence of an aldehydrol, specifically ethylidene glycol, and finally Colles (Chem. Soc. 89,1249—1906) actually isolated crystals of ethylidene glycol

(CH₃CH(OH)₂).

A well known form of chlorinated acetaldehyde is the ordinary chloral hydrate. Evidence has established that here two hydroxyl groups are attached to the same carbon atom.

Further confirmatory evidence of the existence of ethylidene glycol, as well as indications of its particular properties, are found in the study of the action of hydrogen chloride upon acetaldehyde to give ethylidene hydroxy-chloride

(CH₃CH(OH)Cl)

which, upon simply standing at room temperatures, loses a molecule of water and passes over into α — α dichloroethyl-ether

(CH₃CHCl)₂—O—(ClCH₂CH₃).

Here it is to be noted that the tendency for re-action through the hydroxyl group is actually more pronounced under certain conditions than the comparatively simple splitting off of hydrogen chloride and resolution again into original constituents.

The fact that an aldehyde can be converted into its corresponding acid without the utiliza-

5

tion of direct oxidizing agents was established by a number of experiments, of which the following is illustrative.

Experiment

5 An ordinary glass combustion tube, properly fitted for intake and outlet of vapors, was filled with pumice upon which was previously precipitated a mixture of 1 part of aluminum hydroxide and 10 parts of cupric hydroxide. A current of air was passed through this tube while heated to about 270-300° C. so as to effect a complete oxidation of all the contained oxidizable material. Thereupon oxidation was interrupted and 10 while still held at the stated temperature a current of hydrogen was passed through the tube to effect the complete reduction of all copper oxides into metallic copper and to effectively remove all adsorbed or occluded oxygen from within the porous mass. Several hours' time was thus required. Finally the hydrogen was removed from the tube by means of a current of water vapor generated from deaerated water. Into 15 this combustion tube, held at about 250-280° C. was now passed the vapors from a mixture of 44 grams (1 mol.) of pure molecular acetaldehyde and 18 grams (1 mol.) of water. The total effluent vapors, requiring about 30 minutes for single passage, were immediately recycled through 20 the tube. At the end of three complete cycles the products were withdrawn and analyzed as 25 follows. In this analysis allowance was made for the water vapor initially held in the tube.

	Grams
35 Acetic acid.....	14.6
Acetaldehyde	33.0
Hydrogen	0.5
Ethyl acetate.....	0.2
Water	13.5
40 CO ₂ and hydrocarbons.....	0.2
Total (equals acetaldehyde and water)	62

Operating according to the procedure described, the state of equilibrium attained is indicated by 45 the following equation:

50 In the closed system in which this experiment is carried out there occurs a preponderance of acetaldehyde (2 parts—equivalent to 3 mols.) over acetic acid (1 part—equivalent to 1 mol.) in a state of balance. Quantitatively, therefore, 55 we may look upon the reaction as involving 4 mols. of acetaldehyde and 4 mols. of water in the production of 1 mol. of acetic acid and 1 mol. of hydrogen, giving therefore a balanced state between the residual 3 mols. of acetaldehyde and 3 mols. of water over against 1 mol. of acetic acid and 1 mol. of hydrogen. In other words, in the equilibrium equation above an excess of 3 mols. of acetaldehyde and 3 mols. of water is required to drive 1 mol. of acetaldehyde 60 and 1 mol. of water into acetic acid and hydrogen equivalents. By actual weights, therefore, 65 132 grams of acetaldehyde and 54 grams of water are finally balanced against 60 grams of acetic acid and 2 grams of hydrogen. The system indicated by the equation is, however, a closed system and the relative concentration of all ingredients must be in accurate proportion as called for. The concentration of acetic acid obtained by this experiment was found to be approximately 51.0, 70 which closely accords with the theoretical 75

which should result on the conversion of 1 mol. of acetaldehyde out of 4 mols. of this substance into the acid and in the presence of 3 mols. of water extra.

Now the equation, defining the described experiment, requires for equilibrium on the left arm the actual oxidation of acetaldehyde to acetic acid by the addition of elements of water to the carbonyl group, that is the hydration and subsequent removal of 2 hydrogen atoms from the 10 hydrated acetaldehyde or aldehydrol. This is graphically depicted in the following equation:

That this foregoing reaction could be effected so as to secure anything but perceptible quantities of end products in either direction has never been reported. However I have found that, based upon this reaction, an effective process may be developed so that the interaction comes under complete control.

From the foregoing discussion it would appear that the process of producing acid directly from aldehyde without utilizing oxygen or oxygen yielding substances involves only simple hydration and dehydrogenation. In experimentation upon the subject, however, it was found that this was not the case, but that special types of catalysts were required. As pointed out above, metallic copper operated effectively as a dehydrogenative catalyst. It was noted also that silver, palladium, the platinum metals, and also zinc are effective. However certain other well known dehydrogenative catalysts, such for example as manganous oxide and other metallic oxides, are not effective under the low temperature conditions of the present process. These oxide catalysts do not function until the temperature is 40 raised to approximately 350° C. or above. But even here when they do operate undesired side products are concomitantly produced in such quantities as to discourage their employment. Again, if acetaldehyde and water vapor are 45 passed over metallic copper associated with such pronounced hydrative catalysts as the oxides of tungsten, thorium, titanium, molybdenum, and silicon, at temperatures at or below 350° C., there is little or no production of acetic acid. Above 50 350° C. hydration becomes apparent, though only slightly and with the undesired accompaniment of high concentration of carbon dioxide.

Similarly the hydrative catalyst aluminum oxide when used alone is not effective; neither is the catalyst manganous oxide. However, when either one of these two catalysts is mixed with metallic copper, and the other conditions of the run are properly chosen, acetic acid in relatively large quantities is produced.

Again, certain substances combine the properties of dehydrogenation as well as hydration and at first blush would seem to be well suited for the present process. Typical examples of such double functioning catalysts are the oxides of zirconium, manganese and cerium. However when acetaldehyde and water vapors are passed over such oxides alone, at a temperature of 350° or less, no acetic acid is produced. It is only when these oxides are associated with the dehydrogenative metal, such as copper, that conversion of the aldehyde to acid and hydrogen is obtained.

Furthermore it was found that alkali and alkaline earth metal oxides, which display strongly

basic properties, were totally unsuited to the present use.

As a result of considerable experimentation, resulting as noted above in the elimination of certain catalysts as effective catalytic agents, it was found that only weak base metal hydroxides or oxides were serviceable. It furthermore developed that those elements which form amphoteric hydroxides were particularly useful in the process, but here again only such of these as are able to form basic salts with the organic acids in question, under the conditions of the operation, are serviceable. Finally it was found that only those elements forming amphoteric hydroxides and capable of forming basic salts, which salts resist complete hydrolysis under the action of water under 350° C., will serve effectively for the conversion of aldehyde into its corresponding acid.

I have found in short that salts of an organic acid with an amphoteric base, which resist complete hydrolysis under the conditions of operation, are not only particularly well suited but are in fact essential. These substances exert a direct influence upon the conversion. For this reason these amphoteric basic salts are termed partially hydrolyzable or directive catalysts. These directive catalysts, as noted hereinbefore, are without effect upon the conversion of aldehyde to acid save in the presence of the dehydrogenative catalyst.

A study of the periodic system of elements yields but few metals that satisfy the outlined requirements. These elements are as follows: Group 1, copper; Group 2, beryllium, magnesium and zinc; Group 3, aluminum; Group 4, zirconium and the cerium metals; Group 6, chromium; Group 7, manganese; Group 8, iron and cobalt. In the 8th group nickel was found to function at the low temperatures employed but it presented a decided tendency toward carbon dioxide formation, and for this reason is not recommended. Iron and cobalt, as well as copper and zinc, are limited to low temperature operations owing to the high concentration of free hydrogen obtained, under which the higher temperatures reduce their salts to the metallic state.

The necessity for carrying out the present process in the presence of a dehydrogenative catalyst suggested possible aid to be gained by the use of a purely hydrative catalyst. It was found, in conformity with this idea, that the addition to the catalytic mass of oxides of thorium, uranium, vanadium, titanium, molybdenum and tungsten, or salts of these elements with known nonvolatile inorganic acids, such as boric and phosphoric acid, did in fact contribute somewhat to the converting effect of the catalytic mass. However, it was found that the presence of these materials except in minute proportions was in the end disadvantageous because they led to the formation of unsaturated hydrocarbons, due no doubt to the pronounced dehydrative effect of these compounds upon the aldehyde undergoing treatment.

It is found, therefore, in general that as to the catalytic conditions of the treatment it is advantageous to employ a catalytic mass rich in dehydrogenative catalysts and containing two or more of the directive catalysts associated therewith. The hydrative effect of the majority of these stated directive catalytic bases contributes to the ready hydrative activity of the mass. The proper proportions for making up such a mass consist of approximately 10 molecular equivalents of copper, 1 molecular equivalent each of two di-

rective catalysts, 1⁵ molecular equivalent of an insoluble salt of a well known hydrative catalyst, such as copper vanadate or titanate.

It is to be noted, as a further precaution, that insoluble non-hydrolyzable salts of one of the directive bases should not be employed, because by such employment the theoretical total concentration of free hydroxyl group per molecule of catalytic base is lessened. Thus when manganese borate (1 mol.) is employed in the place of manganese hydroxide (1 mol.) in association with copper, only about $\frac{1}{2}$ as much acetic acid is formed from the borate in unit time as when the manganese hydroxide is employed. For this reason no doubt we may ascribe the apparent unfitness of certain basic salts of organic acids to their insolubility.

As has been noted above, the present invention comprises the low temperature conversion of aldehydes to corresponding acids in the presence of certain catalysts and water vapor. The presence of water vapor is highly favorable to the proper practice of the present invention throughout the reaction system. In the first place water vapor affords an excellent means of heat control in the system to avoid the building up of polymerization products, which latter, it will be noted, are particularly favored by mineral salts and acids. The presence of water vapor furthermore minimizes the tendency toward the formation of hydrocarbons from the aldehyde. Again, the presence of water vapor retards some undesirable condensation reactions, as for example the condensation of acetaldehyde into ethyl acetate and also aldol. These condensation reactions are checked or retarded when the vapors are well diluted. It is here to be noted that for this reason the inert gases, such as nitrogen methane and carbon dioxide, may be utilized.

To insure high success of the process it is desirable that any considerable portions of oxygen be excluded. The presence of readily yieldable oxygen material tends to increase the formation of carbon dioxide, as obtained in the older methods by making use of a metallic oxide directly upon the aldehyde for the oxidation of the latter. For this reason absolute assurance against the presence of free oxygen or reducible oxides is recommended and, in the experiment given, was achieved through the prolonged reduction of the catalytic mass by hydrogen just prior to beginning the operation.

It is also to be noted that the presence of finely divided metals, such as copper, may be detrimental to the present reaction. As is known, the presence of this finely divided metal has a tendency to effect decomposition of acetic acid into methane and carbon dioxide, which decomposition begins in the neighborhood of 200° C. However this decomposition is prevented under the conditions of the present process due to the presence of water vapor. Water vapor very materially repressed this action up to temperatures as high as 350° C. In general the presence of water and material absence of alkali, and inorganic acid, define here the optimum conditions. The temperature should be maintained generally below 300° C.

As has been pointed out, the effectiveness and simplicity of the present process depends, in a large measure, upon the discovery of the beneficial effect of the directive catalysts. In the preferred form of procedure therefore an amphoteric hydroxide of a metal, united in part to the organic acid to be produced, is employed. However the

acid radical of the basic salt employed need not necessarily be that corresponding to the acid produced. Thus while, in the preparation of acetic acid, basic hydroxy metal acetates may be used, 5 substitution products of higher fatty acids, such as the propionates may likewise be employed. Such directive catalysts will present a labile hydroxyl group or one presenting a potentially available hydrogenation unit and thus make possible 10 its interaction with the carbonyl group. In another sense the interaction may be considered as

15

20

the withdrawal of a molecule of water between the hydrated form of carbonyl and the hydroxyl of the basic metallic organic salt. This possible interpretation of the mechanics of the reaction between basic manganous acetate and aldehyde, for example, is illustrated by the following equation:

or

75

Now although the aldehydrol possesses but weakly acetic properties, which is midway between alcohol and acidic acid, nevertheless its great concentration in the reaction zone will considerably favor its interaction with the weak directive catalytic bases, such as hydroxy manganous acetate. A likely result of this interaction is a formation of ethyldene hydroxy manganous acetate. Such type of compound is readily hydrolyzed into its original components as the aldehyde and water pass over the basic manganous acetate and even when a quantity of free acetic acid accompanies the incoming vapors. The action of water therefore operates to prevent the actual building up of the ethyldene manganous acetate in the system.

Now, if a dehydrogenative metal, such as copper, is introduced into the reaction zone where this incipient formation of manganous aldehydrol acetate is under way, the evolution of hydrogen is at once noted, which is proved to come only from the aldehydrol portion of the complex salt. One of the products is the normal manganous acetate which, due to the presence of water, is unstable under the operative conditions and loses a quantity of acetic acid through hydrolysis, this quantity corresponding with the excess in acetic acid over and above that constant quantity held under the conditions of operation to constitute its original basic salt. In the basic salts, that is the directive catalysts, the aldehydrol type of compound is markedly soluble, thereby offering the possibility of a high concentration of aldehydrol groups for dehydrogenation when such dehydrogenative influence, as is effected by copper, can be brought into play. The mere solution of such aldehydrol in the free acid with abundance of copper present does not afford conditions germane to the conversion of the aldehyde to acid, excepting at much higher temperatures where decomposition is marked. This basic salt therefore plays a valuable role in effecting a high concentration of aldehydrol-acetate groups within the

same chemical molecule; and hence when an extensive co-surface with copper is presented an ideal condition is afforded for the rapid dehydrogenation and subsequent hydrolysis into acetic acid and the original basic acetate which later again enters the cycle. This cycle will continue as long as the aldehyde and water are introduced.

The continuous operation described above may be illustrated by a set of four equations, which depict the state of equilibrium at definite and successive stages in the operation.

The four equations given above comprehend the operative sphere. Thus the invention presents a procedure for the oxidation of aldehydes at the expense of a molecule of water and consequent liberation of the hydrogen formerly combined in the water. Under the well known prin-

ciple of equilibrium a shift in the concentration of either the water or the hydrogen may be utilized to control the entire process. In summation, with a catalytic mass of manganous hydroxy acetate and copper there is balanced against it 1 mol. of acetaldehyde and 1 mol. of water on one side, and 1 mol. of acetic acid and 1 mol. of hydrogen on the other.

Now it will be observed that the high proportion of acetaldehyde in the end product, as noted in the experiment, is due of course to the presence of hydrogen. In the first experiment operations were carried out in a closed system and no effort was made to displace equilibrium in favor of the formation of acid. However, if we now provide means for withdrawing hydrogen the quantity of acid produced can be increased. Thus by introducing a porous thimble within the reaction zone, the walls of which are permeable substantially only to hydrogen, it becomes a simple matter to remove from 80 to 85% of all hydrogen produced. Such porous thimble may comprise palladium, iron, silica, sillimanite or partially fused earthy material.

In actual operations, therefore, the conditions of the reaction are controlled so as to displace the equilibrium in favor of the production of acetic acid as above stated. A preferred operation is illustrated by the following example.

Example 1A

An ordinary combustion tube provided with an inlet and outlet for vapors was filled with about 50 grams of broken pumice previously cleaned and shaken into a mixture of well washed hydroxides of copper, manganese and chromium in substantially the proportion of 2 gram equivalents of copper, $\frac{1}{2}$ gram equivalent of manganous oxide and $\frac{1}{8}$ gram equivalent of chromic oxide; or approximately 12.6 grams of metallic copper, 1.4 grams of manganous oxide and 1.6 grams of chromic oxide. The impregnated pumice

ice was then dried in air introduced into the tube and thereafter brought to a temperature of 270-300° C. A stream of oxygen or air was passed through the tube and thereafter a current of hydrogen was forced through to displace the oxygen. The flow gas was continued for a sufficient period of time to completely oxidize the oxidizable and subsequently reduce the reducible materials contained in the tube.

10 Vapors of a 20% acetic acid solution were passed through the tube for from 10 to 15 minutes and careful calculation made to ascertain the weight of acetic acid and water remaining within the tube. There was then introduced 15 a mixture of 1 mol. (44 g.) of acetaldehyde and 1 mol. (18 g.) of water in vapor form and the tube was held at temperatures between 260 and 270° C. The vapors issuing from the reaction zone were subjected to dephlegmation and the 20 aldehyde and a portion of the water returned to the system, together with additional quantities of aldehyde and water. The hydrogen gas for the most part was allowed to escape at the cooler end of the dephlegmator. An analysis of 25 the liquid product was found to give the following:

	Grams
Acetic acid	(51.5% concentration) 15
Acetaldehyde	32
Ethyl acetate	.3
Water	14

The process was found to be improved by removing a large portion of the hydrogen as formed 35 from the immediate reaction zone. The conditions of this experiment are given below.

Example 1B

40 Within a combustion tube was provided a porous tube, permeable to hydrogen, which porous tube was closed at one end and at the other end was connected to a vacuum pump. Between the porous inner tube and the combustion tube the coated pumice was placed. The pumice was treated in the same manner as in Example 1A 45 and a mixture of 1 mol. of acetaldehyde and 1 mol. of water in vapor phase was passed through the tube, which was held at the stated temperatures. The reaction mixture was passed through 50 the tube in three or more cycles. During the run about 1 gram of hydrogen was withdrawn through the thimble. An analysis of the liquid product gave the following results:

	Grams
Acetic acid	(76.5% concentration) 29.5
Acetaldehyde	22.2
Water	9

60 It was ascertained that when operating with an excess of water vapor an increased yield of acid was secured, as shown by the following example:

Example 1C

65 The conditions obtaining in this example were the same as those in 1B with the exception that to the catalytic mass was added a small amount of copper vanadate. The operations were carried 70 out under such conditions as to insure the rapid removal of hydrogen from the zone of reaction, and in this run about 1½ grams of hydrogen were thus removed. The charge consisted of vapors of 44 grams (1 mol.) of acetaldehyde and 75 54 grams (3 mols.) of water. Operating in the

manner described a liquid product was secured which analyzed as follows:

	Grams
Acetic acid	(52.6% concentration) 45
Acetaldehyde	11
Water	40.5

It was found that the process was applicable to the conversion of other aliphatic aldehydes, as shown by the following example:

10
Example 2A

In this example the catalysts were the same as those used in Example 1A and the conditions were substantially the same, except that the 15 charge consisted of 58 grams (1 mol.) of normal propionic aldehyde and 18 grams (1 mol.) of water. During the conversion ½ gram of hydrogen was vented from the cooler end of the dephlegmator. Analysis of the liquid products of conversion showed the following:

	Grams
N-propionic acid	(62% concentration) 21
Propionic aldehyde	41
Water	13
Propyl propionate	.2

In order to prove the general utility of withdrawing hydrogen from the zone of reaction when converting aldehydes, tests were conducted in which propionic aldehyde was used in the 30 charge and hydrogen withdrawn as formed by means of the porous thimble, as shown in the following example:

35
Example 2B

In this example the same catalysts were employed as in 1B and the conditions of operation were the same. The charge consisted of 58 grams (1 mol.) of propionic aldehyde and 18 grams (1 mol.) of water. During the treatment approxi- 40 mately 1 gram of hydrogen was removed from the reaction zone through the porous thimble. The liquid products of conversion resulting from this treatment analyzed as follows:

	Grams
N-propionic acid	(80.5% concentration) 37
Propionic aldehyde	28
Water	9
Propyl propionate	.3

In a manner similar to the treatment of acetic acid tests were conducted on the conversion of propionic aldehyde used in an excess of water, as shown in the following example:

55
Example 2C

In this treatment the conditions were the same as those in Example 2B with the exception that in lieu of using 1 mol. of water with 1 mol. of propionic aldehyde, 3 mols. (54 grams) of water 60 were used with 1 mol. (58 grams) of propionic aldehyde. During the operation 1½ grams of hydrogen were withdrawn through the porous thimble. The liquid products analyzed as follows:

	Grams
N-propionic acid	(58% concentration) 55
Propionic aldehyde	15

Water

	Grams
Water	40.5

70

75

From these examples it is readily apparent that the principles of the invention herein described are readily embodied in a simple process which operates very effectively and with relatively high yields.

Not only does the invention comprehend the conversion of aliphatic aldehydes to the corresponding aliphatic acids, but it is likewise applicable to the conversion of aromatic aldehydes to aromatic acids, as is shown in the following example:

Example 3

50 grams of broken pumice, treated with the quantity of catalysts described in Example 1, 10 were packed in a combustion tube, no porous thimble being used. Through this tube vapors of 1 mol. of benzaldehyde (106 grams) and 3 mols. of water (54 grams) was passed and recycled. 15 The temperature of the vapors was held at between 320 and 330° C. During the run 2 grams of hydrogen was vented from the cooler end of the dephlegmator. The liquid products of conversion were analyzed and found to correspond to 20 a 10% yield of benzoic acid.

Similar runs were made with other aliphatic and aromatic aldehydes, such for example as formaldehyde, butylaldehyde and tolylaldehyde, 25 for the purpose of proving the general applicability of the process. In each instance a satisfactory yield of the corresponding acid was obtained.

It was found that the catalysts herein employed remain active over a long period of time, 30 apparently maintained so by reason of the presence of the particular basic salts employed. However, it is to be observed that if desired a rejuvenation or revivification of the catalyst can be secured by admission of a small quantity of 35 oxygen or air.

The diminution or driving down of the temperature for operation, especially below 270° C., makes for elimination of any carbon monoxide that may arise through the action of finely divided metals on acids. Indeed the absence of air and readily reducible oxides renders doubly 40 secure the absence of carbon monoxide throughout the entire system. Thus is assured the prevention of poison effects known to result when 45 carbon monoxide is condensed upon dehydrogenative catalysts.

It should be here noted that the present invention comprehends no such function as that displayed by manganous acetate in its reducing 50 capacity towards peracids and by the subsequent reduction of manganic compounds by aldehyde to a prior state for further duty. Such service is demanded when aldehydes contact with oxygen in order to keep down the concentration 55 of peracids below 1% (the lowermost limits permissible without explosion).

The present invention furthermore comprehends no state of oxidation of organic salts, nor 60 is there any rise in the state of oxidation in view of the total absence of oxygen or oxidizing material.

It is to be observed finally that, in view of the equilibrium conditions of the present process, the reverse action may be secured, that is the action 65 of acid and hydrogen to give an aldehyde. Such results are readily obtainable but, owing to the high adsorption of the hydrogen by the catalytic mass, it is necessary to operate in an excess of hydrogen.

In line with the system of equilibria here set 70 forth, it will be appreciated that it is possible to carry out the process described while employing other starting materials which are convertible by a preliminary treatment to the aldehyde. 75 Thus it is possible to start with, for example, ethyl

alcohol, and by proper treatment convert this to acetaldehyde and thence, by the described treatments, to acetic acid.

It will be appreciated that supporting materials other than pumice may be employed and that in 5 general any siliceous and/or argillaceous materials having the characteristics of pumice may be used.

It will now be observed that an improved method of manufacturing organic acids has been described. The invention is conceived to reside broadly in the concept of preparing organic acids by hydration of the aldehyde and the subsequent dehydrogenation of the intermediate compounds to the corresponding acids, under controlled conditions of temperature and catalysis. Hence, while certain specific examples have been given, it is to be understood that these are merely illustrative of the type of reaction herein involved, and are not to be considered definitive of 20 the limits of the invention.

I claim:

1. A method of preparing organic acids which comprises contacting an aldehyde and water, in vapor phase, with a dehydrogenative catalyst and 25 a directive catalytic base which catalytic base comprises a partially hydrolyzable salt of an amphoteric base and an organic acid.

2. A method of preparing organic acids which comprises contacting aldehyde and water, in 30 vapor phase and below 300 degrees C. with a dehydrogenative catalyst and a directive catalytic base which catalytic base comprises a partially hydrolyzable salt of an amphoteric base and an organic acid.

3. A method of preparing organic acids which comprises contacting an aldehyde and water, below 35 300 degrees C., with a dehydrogenative catalyst and a catalytic mass, which mass comprises a partially hydrolyzable salt of an amphoteric 40 base and an organic acid, and conducting the operation, in the absence of substances which readily yield oxygen.

4. A method of preparing organic acids which comprises contacting an aldehyde and water vapor, at relatively low temperatures, with a dehydrogenative catalyst and a catalytic mass comprising an incompletely hydrolyzable salt of an amphoteric base and an organic acid and conducting the operation in the absence of free 50 oxygen.

5. A method of preparing organic acids which comprises contacting an aldehyde and water vapor, in the presence of a partially hydrolyzable salt of an amphoteric base and an organic acid 55 and then contacting the mass with a dehydrogenative catalyst to produce the corresponding acid.

6. A method of preparing organic acids which comprises contacting an aldehyde and water vapor with a catalytic mass which comprises a partially hydrolyzable salt of an amphoteric base and an organic acid, and dehydrogenating the formed aldehydrol to the corresponding acid by 60 contacting the aldehydrol with a dehydrogenative catalyst while largely removing the free hydrogen produced from the immediate zone of reaction.

7. A method of producing organic acids which comprises passing an aldehyde and water, in 70 vapor phase, and at low temperature in contact with a dehydrogenative catalyst and a salt of an amphoteric base and an organic acid, which salt resists complete hydrolysis under the thermal conditions of the operation.

8. A method of producing organic acids which comprises passing an aldehyde and water, in vapor phase, at temperatures below 350° C. and in the absence of free oxygen, in contact with a 5 salt of an amphoteric base and an organic acid, and a dehydrogenative catalyst; removing hydrogen formed from the zone of reaction, separating unconverted aldehyde from the reaction products and recycling such aldehyde for re-treatment.
9. A method of producing aliphatic acids which comprises contacting an aliphatic aldehyde with a catalytic mass comprising a partially hydrolyzable salt of an amphoteric base and an organic acid and immediately dehydrogenating the hydrated aldehyde by contacting it with a dehydrogenative catalyst and in conducting the operation in one reaction zone and at temperatures between 250° and 280° C.
10. A process of producing acetic acid which comprises passing a mixture of vapors of acetaldehyde and water over a catalytic mass including a dehydrogenative catalyst and a catalytic mass comprising a partially hydrolyzable salt of amphoteric base and an organic acid at temperatures approximately 275° C., continuously withdrawing hydrogen from the zone of reaction and continuously recycling unconverted acetaldehyde to the zone of reaction.
11. A process of producing organic acids which comprises passing a mixture of an aldehyde vapor and water vapor over a catalytic mass including a dehydrogenative catalyst and partially hydrolyzable base and an organic acid, continuously withdrawing hydrogen from the zone of reaction and continuously recycling unconverted aldehydes to the reaction zone.
12. A catalytic mass for the conversion of organic aldehydes to their corresponding acids consisting of a hydroxy compound of an organic acid salt of a metal, such compound being partially hydrolyzable, together with a dehydrogenative agent and a carrier.
13. A method of preparing organic acids which comprises contacting an aldehyde, in vapor phase, with a hydroxy compound of organic acid salt of a metal, such compound being partially hydrolyzable, together with a dehydrogenative agent.
14. A process of preparing organic acids which comprises contacting an aldehyde and water, in vapor phase, with a dehydrogenative catalyst and 10 a hydrative catalyst, and withdrawing hydrogen from the zone of reaction.
15. A process of preparing organic acids which comprises contacting an aldehyde in water, in vapor phase, and below 350° C., with a dehydrogenative catalyst and a hydrative catalyst, and immediately withdrawing the hydrogen liberated from the zone of reaction.
16. A process of preparing organic acids which comprises passing an aldehyde and water, in vapor phase, and below 350° C., in contact with a dehydrogenative catalyst and a hydrative catalyst, immediately withdrawing hydrogen liberated from the zone of reaction, separating acid from the products of conversion and recycling 25 the remainder of said products of conversion.
17. A process of preparing organic acids which comprises contacting an aldehyde and water, in vapor phase, and below 350° C., with a dehydrogenative catalyst and a hydrative catalyst, the 30 hydrative catalyst being in sufficient amount to hydrate substantially all of the aldehyde, and the dehydrogenative catalyst being in sufficient amount to dehydrogenate the hydrated aldehyde.
18. A process of preparing organic acids from 35 aldehydes which comprises contacting an aldehyde and water, in vapor phase, and below 350° C., with a catalytic mass including essentially a dehydrogenative catalyst and a hydrative catalyst, and withdrawing hydrogen liberated during the 40 reaction from the reaction zone.
